UNITED STATES PATENT OFFICE.

ARTHUR WALTER TAYLOR, OF MANCHESTER, ENGLAND.

APPARATUS FOR DISPLAYING GARMENTS AND LIKE ARTICLES.

1,393,327.

Specification of Letters Patent. Patented Oct. 11, 1921.

Application filed March 2, 1920. Serial No. 362,652.

To all whom it may concern:

Be it known that I, ARTHUR WALTER TAYLOR, subject of the King of Great Britain and Ireland, and resident of Manchester, 5 in the county of Lancaster, England, have invented certain Improvements in Apparatus for Displaying Garments and like Articles, of which the following is a specification.

- 10 This invention relates to improvements in apparatus for displaying articles of wearing apparel, in one form for articles such as coats, dresses and the like and in another form for smaller articles such as hats and 15 caps, boots and shoes and the like though I would have it understood that I do not confine myself to the character of the articles which may be displayed as the apparatus is capable of variation in the construction 20 of the supporting details to suit the display of other goods, the main object in all cases being the provision of means by which the articles can be kept in dust-proof show cases while supported on the apparatus and 25 the latter in general be drawn forward out of the case to enable the goods to be shown and inspected.

My invention comprises apparatus supported upon rails within a show case to allow it to be drawn forward or to be returned to the case and to be rotated as desired, means for supporting the objects and means for locking the main supporting frame in certain positions, some of the supporting means being devised for use in show cases apart from the movable and rotatable part of the apparatus.

My invention will be fully described with reference to the accompanying drawings in 40 which,—

Figure 1 is a fragmentary front view, partly in section, of a device constructed according to this invention. Fig. 2 is a side view of the same. Fig. 3 is a plan view 45 of the frame, showing the standard *h* in section on the line 3—3 in Fig. 1.

In accordance with my invention I provide a pair of rails *a* which may form part of, be attached to or be arranged in conjunction with a show case *b* such rails being preferably, though not necessarily, of channeled section so arranged that wheels or rollers *c* may rest in or upon them and be capable of running backward and forward 50 therein and thereon. The rollers are supported on studs or shafts *d* carried by the

main base frame or carriage *e* of the apparatus. The base frame is of any suitable construction and on its upper side is provided with a bracket *f* from which extends upwardly a boss or pillar *g* adapted to support a vertical shaft *h*, the lower end of which rests in a foot-step bearing *i* in the base and preferably a bearing provided with a hard fiber supporting collar or disk *j*. The upper end of the shaft *h* has fixed to it a bracket *v* for supporting rods *w* on which the garments can be suspended by the usual hooked shoulder supports as is well known. The lower end of the shaft carries a cam, or disk *k* notched out at *m* at two diametrically opposite points, such notches acting in conjunction with a spring-controlled catch or slide *n* for holding the disk and consequently the shaft in two different positions. The slide *n* is normally pulled toward the disk by a spring *o* secured to a pin *p* projecting from the bracket *f*. The slide carries a roller *q* to engage with the notches *m* in the disk *k*. The slide *n* operates in conjunction with a fixed angle bracket *r* secured to one of the rails *a*. When the carriage *e* is pushed to the back of the show case the outer end of the slide *n* is just clear of the inner face of the bracket *r*, and the shaft *h* cannot be turned around. Any attempt to do so would cause the cam to force the outer end of the slide *n* against the angle bracket *r*. Hence the rods *w* are kept parallel with the front and back of the show case while the complete apparatus is within. When, however, the carriage *e* is drawn forward to the position shown in Fig. 3 so as to bring the slide *n* beyond the end of the bar *r* then the shaft *h* can be freely turned around to display the garments.

The device can only be pushed back into the show case when the rotatable shaft *h* and its disk *k* have been brought into a position to allow the garment supporting rods *w* to be parallel with the front of the show case, in which position the catch slide *n* moves inwardly so that its roller engages with one of the notches *m* in the disk *k*, locking the parts in position and preventing any possibility of damage to the case or the device.

The apparatus hereinafter described enables coats, dresses and other garments to be suspended from the rods *w* by the usual suspending shoulder bars and hooks such as

are commonly in use for the purpose and allow of any individual garment being examined, removed from the rods and replaced quite easily, while the apparatus is at the 5 front part of the show case. On the other hand the apparatus can be pushed back into the show case and the doors of the latter be closed so as to keep the whole of the garments quite clean and free from dust.

10 What I claim is:

The combination, with a show case, of 15 guide rails arranged in the show case, a frame provided with rollers which run on the said guide rails, a vertical standard journaled in the frame and provided with supports for articles, a notched disk secured to the standard, a spring-pressed slide slidable in the frame crosswise of the rails

and arranged above the said rollers and the tops of the rails, said slide being adapted to engage with the notched disk, and a stop bar secured to the top of one of the said rails opposite the end of the slide and extending in the show case, said stop bar operating to prevent the slide from being retracted to free the notched disk and standard until after the frame has been withdrawn from the show case and the slide has been moved past the outer end of the stop bar.

20 25 30 In testimony whereof I have hereunto set my hand in the presence of a witness.

ARTHUR WALTER TAYLOR.

Witness:

WILLIAM W. TAYLOR.
